Primary Examiner — Barbara Fox*Assistant Examiner* — Mary C Ramirez(74) *Attorney, Agent, or Firm* — Saliwanchik, Lloyd & Eisenschenk(57) **CLAIM**

The ornamental design for a network camera, as shown and described.

DESCRIPTION

FIG. 1 is a front perspective view of a network camera showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings depict portions of the network camera that form no part of the claimed design.

1 Claim, 7 Drawing Sheets(56)
